(57) **CLAIM**

The ornamental design for a frame for a generator, as shown and described.

DESCRIPTION

FIG. 1 is a right side elevational view of a frame for a generator showing our new design.

FIG. 2 is a left side elevational view thereof;

FIG. 3 is a front elevational view thereof;

FIG. 4 is a rear elevational view thereof;

FIG. 5 is a top plan view thereof; and,

FIG. 6 is perspective view thereof.

The broken lines shown represent unclaimed subject matter and form no part of the claimed design.
